J. M. STUCHLIK

DIVIDERS

Filed Oct. 4, 1920

INVENTOR
John M. Stuchlik
BY
Frank J. Schaeffer
Attorney.

UNITED STATES PATENT OFFICE.

JOHN M. STUCHLIK, OF ROUNDUP, MONTANA.

DIVIDERS.

Application filed October 4, 1920. Serial No. 414,630.

To all whom it may concern:

Be it known that I, JOHN M. STUCHLIK, a citizen of the Republic of Czechoslovakia, residing at Roundup, in the county of Musselshell and State of Montana, have invented a new and useful Improvement in Dividers, of which the following is a specification.

This invention relates to improvements in 10 dividers.

It is an object of the invention to create a divider of particular use for carpenters, cabinet makers, joiners, or the like, and to combine with this divider the leg of a T-square or similar implement whereby definite angles may be laid out or the size of angles may be ascertained.

It is also an object of the invention to provide in combination with a pair of dividers, 20 an adjustable member which may be extended either at right angle or at any other suitable angle to one of the legs of the divider or which when in inoperative position may be folded so as to extend parallel to said legs 25 in a different plane and which, therefore, brings the combination tool into a compact shape, in which it will be placed in an ordinary tool box.

It is also an object of the invention to permit the use of the tool as a divider, without necessitating the removal of the T-square.

Other objects of the invention will become apparent by reference to the following specification and the accompanying drawing, 35 which shows an embodiment of the invention.

In the drawing:

Fig. 1 is a front elevation of the improved combination tool; and

Fig. 2 is an end elevation of the same.

The divider comprises the legs 1 and 2, terminating in sharpened points and being pivotally connected to each other by means of head portions which are united by a suitable hinge pin 3. Any preferred form of the legs of the divider or of the pivot connection may be selected.

The leg 1 of the divider serves for supporting, by means of a pivot pin 4, the leg 50 of a T-square 5, which may be provided with suitable graduation marks and which has an enlargement near the inner end. This enlargement has an arcuate slot 6 concentric with the axis of the pivotal support 4, and a 55 straight slot 7 extends approximately

through the whole length of the leg 5 parallel to the edge of the T-square and communicates with the arcuate slot 6. A holding screw 8 extends through the leg 2 of the divider and is provided with a flat head which is held in a suitable countersunk opening; this screw also projecting through the arcuate slot 6 when the divider is closed. A thumb nut 9 on this screw serves for locking the T-square 5 in adjusted position. 65

The enlarged portion of the T-square is, furthermore, provided with a pointer 10 which in the rotation of the square about its pivot point 4 plays over an arcuate scale 11 on an enlargement 12 of the divider leg 70 1. It is obvious, therefore, that the angular relation of the extension 5, with respect to the divider, may be ascertained by reading the position of the pointer 10, with respect to the arcuate scale, and that the extension 75 5 may be folded to occupy the position indicated in dotted lines in Fig. 1, in which position the entire implement can readily be inclosed in a carpenter's tool box or the like. 80

The enlarged portion 12 of the divider leg 1 may be provided with openings 13 to facilitate the rapid adjustment of the leg at certain angles as, for instance, 45° or 135°, at which positions of the leg one of the 85 openings 13 will be in registry with an opening 14 in the enlargement 10 of the leg 5.

When the divider is to be used in the ordinary way as by spreading the legs 1 and 2, the holding screw 8 will slide in the 90 longitudinal slot 7 of the leg 5 without impeding the adjustment of the legs 1 and 2 to any desired width.

I claim:

1. A geometrical instrument comprising 95 a divider having a pair of legs adapted to constitute the head of a T-square; a bar provided with a slot pivotally secured to one of said legs intermediate its ends, and adapted to constitute the blade of the T-square; and means carried by the other of said legs, and engaging said slot, adapted to clamp said bar in any desired angular relation to said legs. 100

2. A geometrical instrument comprising 105 a divider having a pair of legs; a bar pivotally secured to one of said legs, provided with an arcuate slot of substantially 180 degrees and with a straight slot communicating with said arcuate slot at ap- 110

proximately its middle; a threaded stud rigid with the other of said legs, engaging said slots; and a clamping nut engaging said stud adapted to firmly hold said bar in any desired angular relation to said legs.

3. In a device of the class described the combination of a pair of pivoted legs one of which is provided with a plurality of arcuately spaced apertures; a bar pivotally secured to one of said legs, provided with an arcuate slot concentric with its pivot and a straight slot communicating with said arcuate slot, said bar being also provided with an extension having an aperture adapted to register with said first mentioned apertures whereby said bar may be readily positioned at predetermined points about said pivot; and means carried by the other of said legs and engaging said slot,

for clamping said bar in any desired angular relation to said legs.

4. In a device of the character described, the combination of a pair of dividers, a straight edge bar pivotally mounted on one leg of said dividers and having a pointer projecting from said pivot in a direction opposite to that of the bar, said leg having an arcuate enlargement over which said pointer plays, the bar having an arcuate slot concentric with the pivot of the bar and a longitudinal slot communicating with said arcuate slot, and a clamping screw extending through the other leg of the divider into said slot.

In witness whereof, I have hereunto subscribed my name this second day of September, 1920.

JOHN M. STUCHLIK.
